3,016,184 ROTARY COMPRESSORS

Edward C. Hart, Rochester, N.Y., assignor, by mesne assignments, to Scaife Company, Oakmont, Pa., a corporation of Pennsylvania

Filed Jan. 19, 1959, Ser. No. 787,773
7 Claims. (Cl. 230—152)

This invention relates to a new and improved rotary compressor pump and is particularly concerned with a rotary compressor pump of the eccentric vane type. This application is a continuation-in-part of application Serial No. 739,708, filed June 4, 1958, now abandoned.

Rotary compressors of the eccentric or moving-vane type afford substantial advantages, in many instances, as compared with the more conventional piston type gas pumps. Thus, the rotary compressor is essentially better balanced and inherently presents less vibration than piston machines. The rotary pump may also be somewhat simpler in construction and, therefore, less expensive to manufacture than comparable piston compressors. Moreover, for a given power input the rotary compressor is at least theoretically capable of substantially higher efficiency than a piston type compressor.

A particularly advantageous construction for a moving-vane rotary compressor is described and claimed in the co-pending application of William P. Dalrymple and Max W. Kistler, Serial No. 611,328, filed September 21, 1956. The rotary compressor described in that application affords substantially higher efficiency than previously known devices and makes it possible to obtain output pressures of the order of 200 pounds per square inch from a simple single-stage rotary pump. In part, the relatively high efficiency of the Dalrymple et al. device is achieved by forcing oil under pressure into one side of the pump chamber, through axial apertures in the pump rotor and thus into the other side of the pump chamber. By pumping relatively large quantities of oil through the pump chamber in this manner, the pump is held to a relatively low temperature and thus operates more nearly as an isothermal device than is the case with conventional pumps. Moreover, the oil also effectively seals off the several inter-vane areas in the pump and thus materially adds to the pump efficiency.

One difficulty encountered in the operation of the Dalrymple et al. pump, however, relates to the transfer of the cooling and sealing oil from one side of the pump chamber to the other side thereof. If the rotor of the pump is maintained in accurate and exact alignment with the stator, no particular problem is encountered, and the oil is distributed approximately equally on both sides of the rotor. In those instances where the rotor or the rotor shaft can shift axially to even a very slight degree, however, the oil introduced under pressure at one side of the rotor may tend to force the rotor into contact with the opposite side of the pump chamber. When this occurs, undesirable wear may be encountered on the rotor and on the closure member which forms that side of the pump chamber. The rotating friction also results in an excessive load on the motor driving the compressor pump. Furthermore, because all of the rotor clearance is at one end of the rotor, it is extremely difficult to maintain an effective seal between the rotor and the stator. As a consequence, air leakage within the pump further increases the motor load and reduces the output of the pump.

A primary object of the invention, therefore, is a new and improved rotary compressor pump structure which inherently and effectively minimizes or eliminates the aforementioned difficulties in previously known devices of this kind.

A more specific object of the invention is an improved

2

rotor structure which affords a means for distributing oil under pressure to both sides of the rotor and which utilizes the oil itself as a means to maintain the rotor in centered relation within the pump chamber.

Another object of the invention is an improved vane construction for a rotary vane-type compressor pump which co-operates with the lubrication system of the pump to maintain the vanes in aligned position with respect to the rotor and in centered relation within the pump chamber.

An additional object of the invention is a new and improved oil distribution arrangement for a rotary compressor pump which effectively seals the rotor and the rotor vanes with respect to the end walls of the pump chamber and prevents any metal-to-metal contact therebetween.

A particular object of the invention is a new and improved oil distribution system for the rotor of the rotary compressor pump which requires little or no additional expenditure, as compared with previously known devices, in achieving the objectives set forth hereinabove.

Other and further objects of the present invention will be apparent from the following description and claims and are illustrated in the accompanying drawings which, by way of illustration, show a preferred embodiment of the present invention and the principles thereof and what is now considered to be the best mode for applying those principles. Other embodiments of the invention embodying the same or equivalent principles may be used and structural changes may be made as desired by those skilled in the art without departing from the present invention and the purview of the appended claims.

FIG. 1 is an elevation view, partly in cross-section, of a rotary sliding vane gas pump constructed in accordance with one embodiment of the invention;

FIG. 2 is a fragmentary sectional view of the stator and pump chamber of the compressor, taken approximately along line 2—2 in FIG. 1;

FIG. 3 is an end elevation view of the compressor of FIG. 1, with the fan and pulley removed in order to illustrate certain details of the compressor structure;

FIG. 4 is a fragmentary sectional view taken approximately along line 4—4 in FIG. 2;

FIG. 5 is a fragmentary sectional view, similar to FIG. 4, showing the operation of a previously known construction and is utilized for comparison with FIG. 4;

FIG. 6 is a sectional view, similar to FIG. 2, illustrating another embodiment of the invention;

FIG. 7 is a fragmentary sectional view, similar to FIG. 4, but taken approximately along line 7—7 in FIG. 6;

FIG. 8 is a side elevation view of a vane in the embodiment of FIGS. 6 and 7; and

FIG. 9 is an end elevation view of the vane of FIG. 8.

The rotary vane type compressor 10 illustrated in FIGS. 1—3, which comprises a preferred embodiment of the invention, includes an operating shaft 11 rotatably mounted in a pair of main bearings 12 and 13 which in turn are supported in a pair of closure members 14 and 15, respectively. A substantially cylindrical stator member 16 is mounted between the closure members 14 and 15 by suitable means such as a plurality of mounting bolts 17; the substantially cylindrical bore of the stator 16 is closed by members 14 and 15 to define the pump chamber 18 of the apparatus.

As indicated in FIGS. 2 and 3, the stator 16 and the closure member 15 may both be provided with a plurality of heat dissipating or cooling fins 19 to assist in dissipating heat developed during the compression cycle. Shaft 11 extends beyond the compressor housing defined by members 14—16 and is equipped with a suitable mechanical coupling device here illustrated as a pulley 20. It will be understood that any other suitable mechanical

coupling arrangement may be employed; for example, pulley 20 may be replaced by a flexible coupling for inline connection to a suitable motor or engine (not shown) for driving the compressor pump or may comprise any desired gearing arrangement. In addition, a fan 21 is preferably mounted upon the shaft 11 intermediate the coupling 20 and the closure member 14 to impel air over the pump 10 and assist in cooling it. It is also desirable to provide a pair of oil seals 22 and 23 on the shaft 11 to prevent the escape of oil from the compression chamber 18 for reasons apparent by the operational description set forth hereinafter.

The housing of compressor pump 10 also includes a third closure member 25 which may be mounted upon the closure member 15 by any suitable means such as a plurality of mounting bolts 26. Closure members 15 and 25 together define a discharge chamber 27. The compressor housing is supported upon a base 28 which serves as an oil reservoir for the lubricating and cooling system of the compressor. An oil level cut-out switch assembly 29 is also mounted upon reservoir 28. The assembly 29 may comprise a conventional float-actuated switch (not shown) connected to electrical terminals 31. The terminals 31 are employed to connect the switch into a control circuit for the prime mover (not shown) driving the pump 10. The reservoir is also provided with a filler plug 30 and a drain plug 31 and may be equipped with suitable base extensions 32 to permit fastening of the compressor pump to the floor or deck of a suitable supporting structure.

As best seen in FIGS. 1 and 2, the compression chamber 18 is provided with a gas or air intake port 33 which communicates with the pump chamber by means of a pair of passageways 34 and 35 formed in the closure members 14 and 15 respectively; the configuration of passageway 34 is shown in dash outline in FIG. 2. In the illustrated apparatus, the air intake port is located approximately at the top center of the pump chamber 18. An internal pressure port 36 is also provided and communicates with the pump chamber 18, the relative angular displacement between ports 33 and 36 being most clearly indicated in FIG. 2. A passageway 37 connects the internal pressure port 36 with the discharge chamber 27, a stationary baffle 38 preferably being provided at the exit or outlet opening of passageway 37. The internal pressure port 36 is in direct communication with the oil reservoir 28 through an opening 40 in the base of the discharge chamber 27.

The pump 10 is provided with a gas discharge port 41 which extends into and communicates with discharge chamber 27. An oil separator 42 is mounted in substantially encompassing relationship with respect to the discharge port 41 and is thus interposed between the discharge port and the internal gas pressure port 36 of the compressor. Separator 42 comprises a pair of spaced support members 43 and 44 which are utilized to support a porous cylindrical member 45. The cylindrical member may be formed from felt or other suitable fibrous or other porous material. Alternatively, the member 45 may comprise several layers of metal mesh or one or more perforate sheet metal members. The separator 42 is preferably mounted on shaft 11 for rotation therewith, as explained more completely hereinafter. In any event, some means should be provided for rotating the oil separator, whether by direct connection to the compressor shaft as illustrated or by some other equivalent mechanism, since the separator operates by centrifugal action rather than as an oil-trapping device. The details of construction for several different separator structures of this kind are set forth in the aforementioned application of Dalrymple et al.

The compressor rotor structure 50, which is best illustrated in FIG. 2, comprises a rotor member 51 which is provided with eight radial slots 52. Rotor member 51 is circular in cross section and is fixedly mounted upon

the shaft 11 by some suitable means such as a key 53 fitted into a keyway 54 in the shaft 11; the key and keyway construction are illustrated in FIG. 1. As indicated in FIG. 2, eight vane elements 55 are individually slidably mounted within the radial slots 52. The vanes 55 are free to move inwardly and outwardly within the slots. Consequently, when the shaft 11 is rotated at a relatively high speed, the direction of rotation being indicated by the arrow 83, the vanes 55 are impelled outwardly by centrifugal force into contact with the internal surface 56 of the stator 16. The ends of the vanes 55 which contact stator surface 56 are preferably formed with a non-rectangular configuration in order to reduce wear upon the vanes and on the stator surface. In the illustrated apparatus, the leading edges 57 of the blades 55 are beveled at an angle of approximately 15° and the trailing edges 58 are similarly beveled. The contour thus afforded to the ends of the vanes prevents contact between the corner of the vanes and the stator surface and thereby precludes the excessive wear which would otherwise result if the vane ends were rectangular in configuration. The rotor 50 is also provided with a plurality of axial apertures 48 which form a part of the lubricating and cooling system of the pump. Moreover, the trailing surface of each of the vanes 55 is provided with a longitudinal slot 49 which affords a means for oil to escape from the central portion of the vane housing slots 52 to pump chamber 18.

The pump 10 may also include an oil filter 60 which extends into the oil reservoir 28 (see FIG. 3). The upper end of the filter 60 is connected to a conduit 61 which extends for approximately one and one-half revolutions around the compressor housing adjacent closure member 14 and is located directly in the path of air impelled over the pump by fan 21 (see FIG. 1). The oil conduit 61 is connected to a further conduit 62 which may comprise a passageway drilled into or otherwise formed in closure member 14. The conduit 62 terminates in a plurality of relatively small oil injection or inlet ports 63 which open into the pump chamber 18. The oil inlet ports 63 are preferably located in the compression portion of chamber 18. The oil conduit 61 is provided with a multiplicity of heat-conducting fins 64 preferably distributed along the entire length of the conduit; consequently, the oil conduit serves as a heat exchanger for the oil, transferring heat from the oil to the air stream blown over the conduit by fan 21.

When the compressor illustrated in FIGS. 1-3 is placed in operation, the oil reservoir 28 is first filled with oil through the opening indicated by the plug 30 (FIG. 3). As the oil level rises, the switch 29 is closed, thereby avoiding an open circuit in the energizing system for the compressor. Of course, the oil reservoir should be filled somewhat beyond the point necessary to close the switch in order to afford a margin of safety in operation of the compressor pump. After the oil reservoir has been filled, the prime mover (not shown) for the compressor, which is connected to the pump through mechanical coupling 20, may be energized to start the pump in operation. The shaft 11 is thus driven in the direction indicated by arrows 83 in FIGS. 1-3. Consequently, the rotor structure 50 is rotated in the direction indicated by arrow 83 within the pump chamber 18 and the filter 42 is similarly rotated within the discharge chamber 27, since both of these elements are affixed to the operating shaft.

The compression cycle of the pump is best understood by reference to FIG. 2. The air or other gas to be pumped and compressed enters the pump through the gas intake port 33 in stator 16 and is admitted to the pump chamber 18 through the passageways 34 and 35 in the closure members 14 and 15. In the illustrated embodiment, the intake passageways communicate directly with an intake section 93 encompassing approximately 90° of arc of the pump chamber 18. The air or other gas is entrapped between adjacent vanes 55 and consequently

is impelled in the direction of rotation indicated by arrow 83, the vanes being held in contact with stator surface 56 by centrifugal force. During approximately the first 90° of rotation, coinciding with the intake section 93, the overall volume entrapped by the rotor member 51 and stator surface 56 increases progressively.

In approximately the next 30° of rotation, comprising transition section 94, the relative spacing between the rotor and stator of the pump remains essentially constant and the gas in chamber 18 is neither compressed nor expanded. Subsequently, however, in the compression section 100, the spacing between the stator and rotor decreases and the air entrapped between the vanes is compressed. The internal pressure port 36, which opens into the compression chamber 18 at the portion thereof coincident with the discharge section 101 of the stator surface contour, permits discharge of the compressed gas into passageway 37, the discharge portion of the compression chamber extending for approximately 40°. For the remaining arc of the pump chamber 18, comprising sealing section 99, the rotor member 51 and stator surface 56 have approximately the same contour and are closely fitted together so that the internal pressure port 36 is effectively sealed off from the air intake port 33.

As indicated in FIG. 1, the compressed gas passes from the internal pressure port 36 into discharge chamber 27 by means of conduit 37. The discharge chamber 27 communicates directly with the oil reservoir 28 through the opening 40; consequently, a relatively high pressure is maintained upon the oil in the reservoir. This pressure forces the oil from the reservoir through filter 60, into the conduit 61—62 and out through the oil ports 63. The oil inlet ports are located at points such that the internal air pressure within the portion of chamber 18 to which the oil is admitted is substantially lower than the final discharge pressure of the pump in order that relatively large quantities of oil may be forced into the compression chamber. Because the oil inlet ports are aligned with the axial openings 48 in the rotor member 51, the oil flows under pressure through these openings and thus is conveyed to the side of the pump chamber adjacent closure member 15 as well as to that adjacent closure member 14 in which the inlet ports are located. Preferably, the oil inlet ports coincide with a part of the compression portion 100 of pump chamber 18, since admission of the oil during the intake portion of the compression cycle could result in flooding of the pump. Location of the oil inlets in the high compression section of the pump chamber, on the other hand, would preclude introduction of sufficient quantities of oil.

The oil introduced into the compression chamber 18 through ports 63 serves a dual function. The oil, of course, lubricates the vanes of the compressor and prevents them from "freezing" to the internal surface 56 of stator member 16. At the same time, and as a corollary to the lubricating action, the oil effectively seals the rotor vanes to the stator surface and minimizes leakage of entrapped air from between one pair of vanes to the following section of the pump chamber. In the sealing section 99 of the pump chamber, the oil affords an oil seal between the peripheral surface of rotor member 51 and the interior surface of the stator, thereby materially aiding in isolating the intake and outlet ports of the pump chamber and increasing the efficiency of the pump. Of course, a certain amount of oil inevitably finds its way into the base portions of the slots 52 behind the vanes 55. This oil, which might otherwise impede radial movement of the vanes, is permitted to escape from the slots 52, as the vanes are driven inwardly during the compression portion of the pump operating cycle, by the provision of the slots 49 in the trailing surfaces of the vanes.

The relatively large quantities of oil introduced into pump chamber 18 through ports 63 also perform a cooling function. The oil is cooled a substantial amount before introduction into the pump chamber, since it is re-

quired to pass through the heat exchanger comprising the convolutions of the conduit 61 and its heat-radiating fins 64, which are disposed directly in the path of air from the fan 21. Consequently, the oil introduced into the pump chamber is substantially lower in temperature than would be the case if it were conveyed directly from the oil reservoir into the pump chamber with no heat exchanger being provided. The relatively large quantities of pre-cooled oil introduced into pump chamber 18 effectively absorb a substantial portion of the heat inevitably generated in the compression cycle and permit operation of the compressor more nearly at an ideal isothermal level than would otherwise be possible. Accordingly, the cooling action of the oil materially adds to the efficiency of the compressor pump.

The presence of the relatively large quantities of oil desired for cooling purposes within the compressor inherently leads to the entrainment of substantial quantities of oil within the compressed gas which is conveyed into the discharge chamber 27 through conduit 37. Consequently, the compressed gas output from the pump, in the absence of special oil-separator apparatus, would be completely unsatisfactory for many applications, particularly in paint spraying and the like. Virtually all of the entrained oil, however, is separated from the compressed gas and is returned to the oil reservoir in the illustrated apparatus. A substantial portion of the entrained oil collects upon baffle 38 as the compressed gas impinges upon that element; this oil drains back into the oil reservoir 28 through the opening 40. Subsequently, as the compressed air passes from the discharge chamber 27 through the perforate member 45 toward the discharge port 41, virtually all of the remaining entrained oil is separated from the compressed gas by rotary separator 42. Unlike a stationary porous or other perforate filter, however, the filter element 45 does not become clogged with the oil. Rather, the relatively high-velocity angular motion of the separator caused by its mounting upon shaft 11 is in turn imparted to the entrained oil and impels the oil particles outwardly from the separator by centrifugal action. Thus, the oil is centrifugally removed from the compressed gas and is returned to the reservoir through the opening 40.

In addition to cooling the oil passing through the heat exchanger 61, 64, the air blown over compressor 10 by fan 21 effectively cools the external surface of the compressor and helps to maintain it at a relatively low operating temperature, heat dissipation from the pump being aided by the provision of the heat-radiating fins 19. In addition, the oil reservoir 28 is preferably provided with a plurality of fins 89 to aid in dissipation of heat from the oil reservoir. If the oil level in reservoir 28 reaches a dangerously low level, the cut-out switch 29 is actuated to open the energizing circuit of the prime mover of the compressor and thus prevent damage to the compressor which might otherwise result.

The simple single-stage rotary vane compressor pump 10, as thus far described, corresponds substantially to that of the aforementioned Dalrymple et al. application. The pump affords relatively high outlet pressures of the order 200 p.s.i.g. in a single compact stage and thus provides much higher pressures than other previously known devices. The greatly increased efficiency of the compressor is achieved partly by the circulation of substantial quantities of oil through the compression chamber 18, the oil functioning as a coolant, a sealing agent, and as lubricant.

In some instances, however, it has been found that the oil introduced into the compression chamber 18, through the oil inlet ports 63, tends to shift the rotor 51 axially away from the end closure member 14 and into contact with the closure member 15. This condition is illustrated in FIG. 5. As indicated therein, the oil emerging from the inlet ports, under pressure, tends to force the rotor 51 to the left and into contact with

the end closure member 15. In theory, this could be prevented by adequately anchoring the rotor upon the operating shaft 11 and by making sure that the shaft 11 cannot move in an axial direction with respect to the end closure members 14 and 15 and the stator 16. As a practical matter, however, it is extremely difficult to obtain this objective by mechanical measures intended to prevent axial movement of the rotor or its shaft. This is particularly true in view of the fact that the clearance between the rotor and stator, in a useful pump, is extremely small, the total difference between the axial length of the rotor 51 and the width of the pump chamber being of the order of 0.005 inch.

As indicated by the arrows 159 in FIG. 5, the oil forced into the pump chamber through the inlet port 63 may enter one of the axial openings or conduits 48 in the rotor 51 and may travel therethrough to the side of the rotor adjacent to the end closure member 15. If the oil pressure has forced the rotor into contact with the end closure member, however, the oil cannot flow between the closure member and the rotor. Rather, it tends to be forced out backwardly through the conduit 48 and into the space between the rotor 51 and the closure member 14. Thus, the total effect of the oil is to maintain the rotor 51 in contact with the stationary member 15, giving rise to excessive wear, excessive heat losses, and an overall drop in efficiency of the pump. The loss of efficiency is also increased by the fact that the space 151 between the rotor 51 and the closure member 14 becomes relatively large and substantially prevents maintenance of a good seal in this portion of the pump.

FIGS. 2 and 4 illustrate the modified rotor construction of the invention, which effectively and inherently overcomes the problems and difficulties presented by the construction of FIG. 5. As best indicated in FIG. 2, the face of the rotor 51 adjacent the closure member 15 is provided with a plurality of relatively shallow pressure-equalizing depressions 152. These depressions 152 are located immediately adjacent to and in communication with the axial oil conduits or openings 48. Furthermore, and as shown in FIG. 4, a similar plurality of relatively shallow pressure-equalizing depressions 153 are preferably formed on the opposite side of the rotor 51 immediately adjacent to the closure member 14. The depressions 153 on the side of the rotor adjacent to the closure member 14 are not completely essential insofar as achieving the major objectives of the invention is concerned. However, the provision of the depressions on both sides of the rotor makes balancing of the rotor a much simpler matter than would otherwise be the case. Moreover, with depressions formed on both sides, the rotor may be mounted on the shaft 11 without regard to which way it faces.

With this extremely simple change in the rotor 51, the effect of the high pressure oil, as it enters the pump chamber from the inlet ports 63, upon the axial alignment of the rotor is very substantially changed. As before, the oil flows under pressure from the port or ports 63 through the rotor oil conduits 48 to the side of the rotor adjacent the closure member 15. In this instance, however, it is not possible for the rotor to contact the closure member 15 to an extent sufficient to keep the high pressure oil within the conduit 48 and thus block the conduit. Rather, the oil enters the shallow depression 152 and consequently exerts a force, upon the closure member 15 and the rotor 51, tending to force the rotor to the right as seen in FIG. 4. A substantially equal force is exerted upon the rotor by the introduction of oil, under pressure, into the depressions 153 and the normal space between the closure members 14 and the rotor 51. In this manner, the hydraulic pressures upon the two sides of the rotor 51 are substantially equalized and the rotor tends to remain in the center of the pump chamber in equally spaced relation with respect to both of the closure members 14 and 15.

By using the pressure-equalizing depressions 152, the rotor 51 may be accurately held in the center of the pump chamber with a very small clearance at each of its opposed faces. Consequently, it is possible to effectively seal both sides of the rotor with respect to the remainder of the pump chamber and also to prevent metal-to-metal contact at the rotor faces. It should be understood that the clearances at the two sides of the rotor, as shown in FIG. 4, have been exaggerated in the drawing; actually the effective clearance in each instance is preferably of the order of 0.002 inch.

In addition to preventing shifting of the rotor within the pump chamber, the inventive rotor structure makes it possible to increase the speed of operation of the pump to a substantial extent because of the better seal afforded by the oil on the opposite sides of the rotor. Consequently, the pump provides increased air output without overloading the motor or other prime mover which drives the pump. Despite the fact that only a relatively small portion of the rotor face is occupied by the pressure-equalizing depressions 152, the rotor is effectively balanced in its axial relation to the pump chamber. In this regard, it should be noted that the pressure-equalizing depressions 152 should be at least equal in area to the cross-sectional area of the conduits 48. Although it may be expected that much larger pressure-equalizing depressions would be required, this has been found to be unnecessary.

FIGS. 6-9 illustrate a preferred embodiment of the invention which in many respects is essentially identical with that of FIGS. 1-4, but which also includes provision for dynamic balancing or centering of the vanes of the compressor pump. Because many of the elements of the embodiment of FIGS. 6-9 may be essentially similar to those of the first described embodiment, corresponding reference characters have been used in many instances.

The sectional view of FIG. 6, which corresponds generally to that of FIG. 2, shows a compressor pump 200 comprising a stator 16 which is secured to an end closure member 15 (FIG. 7) by means of the bolts or other retainers 17. A second end closure member 14 is mounted on the opposite side of the stator to afford an enclosed pump chamber 18 within which the rotor member 51 is mounted. The rotor member 51, as best shown in FIG. 6, is essentially similar to that described hereinabove in conjunction with FIGS. 1-4 and preferably includes a plurality of longitudinal apertures 48 which form a part of the lubricating and cooling system of the pump. Moreover, the rotor member 51 is preferably provided with a series of pressure-equalizing depressions 152 which are located immediately adjacent to and in effective communication with the axial conduits 48. The rotor member 51, as before, is mounted upon a shaft 11 and is rotated in the direction indicated by the arrow 83 during operation of the pump.

In the embodiment of FIGS. 6-9, the one end closure member 14 is again provided with an internal oil conduit 62 which communicates with the internal chamber of the pump through a series of oil ports 63. As before, oil is fed into the conduit 62, under pressure, through suitable means such as the oil line 61. The oil feed for the pump may comprise an oil reservoir which communicates with the high pressure end of the pump (see FIG. 1). The pump 200 is provided with an intake port 33 which communicates with the chamber 18 through suitable openings 65 in the end closure members, such as the opening 34. The internal pressure port 36 and discharge passage 37 of the pump are substantially as described hereinabove.

The construction of the vanes 255 which are utilized in the pump 200, however, is different from that of the vanes 55 in the previously described embodiment. Each of the vanes 255, as shown in detail in FIGS. 8 and 9, is provided with a pair of channels or indentations 249 in the rear surface thereof to provide for pressure equalization between the base 250 and the tip 251 of the blade.

Thus, the channels 249 correspond to the channels 49 in the previously described vane structures.

In addition, however, each of the vanes 255 is provided with a longitudinal depression or conduit 252 in the base thereof. This longitudinal channel extends for the full length of the blade. In addition, a pair of relatively shallow pressure-equalizing depressions 253 and 254 are provided in the end faces 257 and 258 of the blade, respectively. As before, the vanes 255 are mounted in the rotor member 51 within a series of axial slots 52 in the rotor member.

The contour of the tip or end portion 251 of each blade 255 is also somewhat different from that of the previously described blades. Instead of using double edges, the tip portion 251 of each blade 255 is finished with an arcuate radius which is relatively large compared to the width of the blade but substantially smaller than the radius of the rotor member 51. This configuration has been found to afford less wear in operation of the pump and to facilitate obtaining good sealing contact between the ends of the vanes and the internal surface of the stator member 16.

In operation, the several conduits 249, 252, 253, and 254 are effective to hold each of the vanes 255 in the center of the pump chamber 18 with a very small clearance between the vane surfaces 255 and 258 and the end closure members 14 and 15, respectively. This relationship can best be seen in FIG. 7. As illustrated therein, oil is forced under pressure from the conduit 62 through one of the oil ports 63 into the slot 52 in which the vane 255 is located. The oil is forced under pressure into both of the pressure-equalizing depressions 253 and 254 and exerts a force, upon each side of the vane, tending to force the vane away from the adjacent end closure members. The hydraulic pressures at the two sides of the vane are substantially equal, with result that the vane tends to remain centered longitudinally in the pump chamber 18 and in equally spaced relation with respect to the two closure members 14 and 15. The conduit or depression 252 in the base of the vane assures complete equalization of pressures even if the vane approaches the bottom of the rotor slot 52 in which it is mounted, and prevents cutting off of communication between the two sides of the vane. Moreover, and as in the case of the hydraulic sealing arrangement described hereinabove for the rotor member 51, the oil forced into the end slots in the vane effectively seals the sides of the vane with respect to the remainder of the pump chamber and prevents metal-to-metal contact with the end closure members. As in the case of FIG. 4, clearances of the two sides of the vane 255 with respect to closure members 14 and 15 have been exaggerated in FIG. 7. Preferably, the effective clearance is of the order of 0.002 inch.

The construction of the vanes 255 makes it possible to maintain the vanes in accurate alignment with respect to the rotor member 51 without providing any mechanical arrangement or retainer means for this purpose. Only relatively shallow depressions are required in the vanes and, as indicated in FIGS. 8 and 9, the depressions 253 and 254 need not extend for the full height of the vanes. Of course, the hydraulic pressure positioning arrangement for the vanes may be employed in conjunction with a rotor which is positioned within the pump only by mechanical means, but by far the most advantageous arrangement is that shown in FIG. 6, in which hydraulic positioning of the vanes is combined with a correspondingly similar rotor alignment system.

Hence, while the preferred embodiments of the invention have been illustrated and described, it is to be understood that these are capable of variation and modification, and I therefore do not wish to be limited to the precise details set forth, but desire to avail myself of such changes and alterations as fall within the purview of the following claims.

I claim:

1. A rotary vane-type gas compressor pump compris-

ing: a pair of end closure members; an annular stator member mounted intermediate said end closure members to define therewith a pump chamber; an oil conduit, extending through one of said end closure members and terminating in an oil inlet port opening into one side of said chamber; a cylindrical rotor member rotatably mounted eccentrically in the chamber between said end closure members, said rotor having a plurality of radially evenly spaced longitudinal vane-receiving slots therein, 10 said rotor member further having a plurality of relatively small axial conduits extending therethrough for transmitting oil from said oil inlet port to the opposite side of said chamber, said rotor member further having a plurality of shallow pressure-equalizing depressions of substantially identical size formed in the opposed faces thereof adjacent to and communicating with said axial conduits, each of said depressions being equidistantly spaced between said slots whereby said rotor is rotationally balanced; and means for introducing oil, under pressure, through said oil conduit, said oil inlet port and said axial rotor conduits, into both sides of said pump chamber.

2. A rotary vane-type gas compressor pump comprising: a pair of end closure members; an annular stator member mounted intermediate said end closure members to define therewith a pump chamber; an oil conduit, extending through one of said end closure members and terminating in an oil inlet port opening into one side of said chamber; a cylindrical rotor member rotatably mounted eccentrically in the chamber between said end closure members, said rotor member having a plurality of radially evenly spaced longitudinal vane-receiving slots therein, 15 said rotor member further having a plurality of relatively small axial conduits extending therethrough for transmitting oil from said oil inlet port to the opposite side of said chamber, said rotor member further having a plurality of shallow pressure-equalizing depressions of substantially identical size, formed in the opposed faces thereof adjacent to and communicating with said axial conduits, each of said depressions being equidistantly spaced between said slots whereby said rotor is rotationally balanced; and means for introducing oil, under pressure, through said oil conduit, said oil inlet port and said axial rotor conduits, into both sides of said pump chamber.

3. A rotary vane-type gas compressor pump comprising: a pair of end closure members; an annular stator mounted intermediate said end closure members to define therewith a pump chamber; an intake port for admitting gas into said pump chamber; an internal pressure port communicating with said chamber at a location circumferentially displaced from said intake port; an oil conduit, extending through one of said end closure members and terminating in a plurality of oil inlet ports opening into one side of said chamber at a point intermediate said intake and pressure ports; a cylindrical vane-type rotor rotatably mounted eccentrically in the chamber between said end closure members, said rotor member having a plurality of radially evenly spaced longitudinal vane-receiving slots therein, 20 said rotor further having a plurality of relatively small axial conduits extending therethrough for transmitting oil from said oil inlet port to the opposite side of said chamber, said rotor further having a plurality of shallow pressure-equalizing depressions of substantially identical size formed in the opposed faces thereof adjacent to and communicating with said axial conduits, each of said depressions being equidistantly spaced between said slots whereby said rotor is rotationally balanced; and means for introducing oil, under pressure, through said oil conduit, said oil inlet port and said axial rotor conduits, into both sides of said

pump chamber, said means comprising an oil reservoir connected to said pressure port and to said oil conduit.

4. A rotary moving-vane gas compressor pump comprising: a pair of end closure members; an annular stator member mounted intermediate said end closure members to define therewith a pump chamber; an oil conduit, extending through one of said end closure members and terminating in an oil inlet port opening into one side of said chamber; a cylindrical rotor member rotatably mounted eccentrically in the chamber between said end closure members, said rotor member having a plurality of radially evenly spaced longitudinal vane-receiving slots therein, said rotor member further having a plurality of relatively small axial conduits extending therethrough for transmitting oil from said oil inlet port to the opposite side of said chamber, said rotor member further having a plurality of depressions of substantially identical size formed in the face thereof adjacent said opposite side of said chamber, said depressions being located adjacent to and communicating with said axial conduits, each of said depressions being equidistantly spaced between said slots whereby said rotor is rotationally balanced; and means for introducing oil, under pressure, through said oil conduit, said oil inlet port and said axial rotor conduits, into both sides of said pump chamber.

5. A rotary moving-vane gas compressor pump comprising: a pair of end closure members; an annular stator member mounted intermediate said end closure members to define therewith a pump chamber; an oil conduit, extending through one of said end closure members and terminating in an oil inlet port opening into one side of said chamber; a cylindrical rotor member rotatably mounted between said end closure members, said rotor member having a plurality of longitudinal vane-receiving slots therein and further having a plurality of relatively small axial conduits extending therethrough for transmitting oil from said oil inlet port to the opposite side of said chamber, said rotor member further having a corresponding plurality of depressions formed in the face thereof adjacent said opposite side of said chamber, said depressions being located adjacent to and communicating with said axial conduits; a plurality of vanes disposed in respective ones of said slots and radially and longitudinally movable relative to said rotor member, each of said vanes having a depression in the end face adjacent said opposite side of said chamber and communicating only with the slot in which the vane is located; and means for introducing oil, under pressure, through said oil conduit, said oil inlet port, said vane-receiving slots, and said axial rotor conduits, into both sides of said pump chamber and into both said rotor member depressions and said vane depressions to maintain said rotor member and said vanes in centered relation between said end closure members.

6. A rotary moving-vane gas compressor pump comprising: a pair of end closure members; an annular stator member mounted intermediate said end closure members

to define therewith a pump chamber; an oil conduit, extending through one of said end closure members and terminating in an oil inlet port opening into one side of said chamber; a cylindrical rotor member rotatably mounted between said end closure members, said rotor member having a plurality of vane-receiving longitudinal slots therein; a plurality of vanes individually disposed in respective ones of said slots and radially and longitudinally movable relative to said rotor member, each of said vanes having a shallow pressure-equalizing depression in each end face thereof open only to the slot in which said vane is located; and means for introducing oil, under pressure, through said oil conduit, said oil inlet port and said rotor slots, into both of said depressions on each vane to maintain each vane in centered relation relative to said end closure members.

7. A rotary moving-vane gas compressor pump comprising: a pair of end closure members; an annular stator member mounted intermediate said end closure members to define therewith a pump chamber; an oil conduit, extending through one of said end closure members and terminating in an oil inlet port opening into one side of said chamber; a cylindrical rotor member rotatably mounted between said end closure members, said rotor member having a number of longitudinal vane-receiving slots therein and further having a plurality of relatively small axial conduits extending therethrough for transmitting oil from said oil inlet port to the opposite side of said chamber, said rotor member further having a corresponding plurality of pairs of shallow-pressure-equalizing depressions formed in the opposed faces thereof adjacent to and communicating with said axial conduits; a plurality of vanes individually mounted in respective ones of said slots and radially and longitudinally movable relative to said rotor member, each of said vanes having a longitudinal oil-transmitting channel in the base thereof and further having a pair of shallow pressure-equalizing depressions in the opposite end faces thereof, said vane end face depressions communicating only with said channel; and means for introducing oil, under pressure, through said oil conduit, said oil inlet port, said oil-transmitting channels, and said axial rotor conduits, into both sides of said pump chamber and into both said rotor member depressions and said vane depressions to maintain said rotor member and said vanes in centered relation relative to said end closure members.
